(57) **CLAIM**

The ornamental design for a connector, as shown and described.

DESCRIPTION

FIG. 1 is a front view of a connector, showing our new design;

FIG. 2 is a back view thereof;

FIG. 3 is a left view thereof;

FIG. 4 is a right view thereof;

FIG. 5 is a top view thereof;

FIG. 6 is a bottom view thereof;

FIG. 7 is a front perspective view thereof; and,

FIG. 8 is a right perspective view thereof, shown in an environmental use.

The dot-dash broken lines in FIGS. 1 and 7 illustrate boundaries surrounding the claimed design, and are not part of the claimed design. The portions shown lightened outside of the dot-dash broken lines form no part of the claimed design.

The dotted broken lines in FIGS. 1 and 7 illustrate boundaries surrounding the disclaimed design, and are not part of the claimed design. The portions shown lightened inside the dotted broken lines form no part of the claimed design.

1 Claim, 8 Drawing Sheets
